UNITED STATES PATENT OFFICE.

ELMER F. CASSEL, OF SEATTLE, WASHINGTON.

CIPHER-CODE.

SPECIFICATION forming part of Letters Patent No. 657,587, dated September 11, 1900.

Application filed June 23, 1900. Serial No. 21,319. (No model.)

To all whom it may concern:

Be it known that I, ELMER F. CASSEL, of Seattle, in the county of King and State of Washington, have invented certain new and useful Improvements in Cipher-Codes; and I do hereby declare the following to be a full, clear, and exact description of the invention, such as will enable others skilled in the art to which it appertains to make and use the same.

10 This invention relates to certain new and useful improvements in cipher-codes for use in transmission of cable, telegraphic, and other forms of written messages.

A careful study of the English language develops the fact that there are many words and phrases or expressions which are capable of universal and interchangeable employment and combination with a large number of words and expressions of every-day use.

20 One object of my invention is to group these primary and auxiliary expressions in such manner that they can be systematically and universally combined one with the other into grammatical sentences and to indicate 25 the same by a cipher-word which will serve as an index of both the primary and auxiliary expressions intended to be so combined.

A further object is to produce a simple and concise cipher-code which is particularly 30 applicable for the transmission of tabulated matter.

A further object is to provide a cipher-code which can be readily and easily comprehended and accurately used and in which liability to 35 error in transmission is reduced to a minimum or entirely overcome.

The invention will be hereinafter fully set forth, and particularly pointed out in the claims.

40 In the accompanying drawings, Figures 1 and 2 are views of consecutive pages of my improved cipher-code. Figs. 3 and 4 are views illustrating the number-code.

Referring to the drawings, A designates a 45 series of what I term "primary" words or expressions, the same being arranged in a vertical column, as shown. Opposite each of said words or expressions is placed that portion B of the cipher-word by which the particular 50 line or definition is indicated, said line or cipher words being arranged in a vertical col-

umn C. Said line-words are the same for each page. The auxiliary words or expressions D are also arranged in columns E, line-words F being placed opposite each and arranged in columns G and H, the line-words being different in each column.

In practice when it is desired to transmit a cipher message the same is indicated by a cipher-word which is made by uniting the 60 line-words indicating the primary and auxiliary expressions, the cipher-word thus formed serving as an index to the two expressions. To illustrate, it will be assumed that the following message is to be transmitted, to wit: 65 "Unless you can answer immediately I cannot entertain any proposition." Said message would be contained in the two cipher-words "Snackfag Stabfay," the first portion or syllable of each of said words indicating 70 the auxiliary words or expressions and the latter portion the primary words or expressions. It is obvious, however, that this arrangement can be reversed without departing from the spirit of my invention. When 75 it is desired to use the primary expressions alone, the same may be indicated by cipher-words, which are formed by combining the page-word I with the line-word indicating the desired definition.

In Figs. 3 and 4 I have shown a modified form of my improved cipher-code, the same being particularly adapted for the transmission of numbers for any purpose whatever. The numbers are preferably arranged in columns J K, the primary numbers ranging from 80 "000" to "999" and the auxiliary numbers from "1" to "999," as shown, each number being indicated by a line-word L, which line-words are arranged in columns, as heretofore 85 described. When it is desired to transmit a number, the same is written down by the operator and divided from the right into groups of three figures, the ordinary method of numerical notation. The cipher-word is then 90 formed by consecutively uniting the line-words indicating the respective groups. For example, the number "110,996" would be indicated by the word "Soletail," the syllable "sole" representing "110" and the syllable 95 "tail" representing "996." From this it will be seen that any conceivable number of six

figures can be accurately transmitted by the use of a single cipher-word, a result impossible to accomplish under present methods without the use of nine hundred and ninety-nine thousand nine hundred and ninety-nine cipher-words, the impracticability of which is apparent.

The advantages of my invention are apparent. It will be particularly noted that by the arrangement of words and phrases into primary and auxiliary groups an exceedingly-large number of sentences of common use can be contained in a few pages, where they otherwise would require a volume of inconvenient and unwieldy proportions. To illustrate, presuming the use of a code-book in which each double page contains sixty primary words or expressions and two columns of sixty auxiliary words or expressions capable of use in connection with any one of said primary words or expressions, said double page would contain seven thousand two hundred code expressions, which under the forms now in general use would require one hundred and twenty pages of sixty lines each. By following this out it will be readily seen that a cipher-code of one hundred and twenty thousand definitions can be compiled from one thousand verbs or primary expressions of every-day use when arranged to be combined with one hundred and twenty auxiliary phrases. These can all be arranged on twenty pages, whereas the forms now in general use would require a code-book of two thousand pages with sixty lines to a page. The advantages of my invention are further enhanced by the fact that this arrangement reduces the number of cipher-words to be employed to a mere fraction of those required by methods now in use, making it possible to select such words as will be practically without liability of error in transmission, one of the greatest causes of error in telegraphic transmission of cipher-words now in use being that they are formed of a meaningless aggregation of letters, the error arising principally from the fact that the receiving operator has nothing to guide him in determining whether or not he has received it correctly. In my system this difficulty is entirely overcome by the use of simple line-words which are capable of literal translation, but which when combined form cipher-words absolutely without literal meaning. Another very important advantage lies in the fact that the primary expressions employed by my system are capable of use alone or in combination with the auxiliary phrases, as desired.

I claim as my invention—

1. A cipher-code comprising a series of definitions each indicated by a line word or syllable, said line words or syllables having no

cipher meaning unless combined with another line word or syllable.

2. A cipher-code comprising a series of definitions arranged in pages or groups, and page and line words or syllables indicating the same, said page and line words having no cipher meaning unless combined with another page or line word.

3. A cipher - code comprising a series of groups of definitions which may be used alone or in combination, one with the other, as set forth.

4. A cipher - code comprising a series of groups containing a series of definitions each indicated by a line word or syllable representing part of a cipher-word, said definitions being capable of use alone or in combination, one with the other, as set forth.

5. A cipher-code comprising a series of definitions of universal use and application segregated into groups of primary and auxiliary words or phrases susceptible of universal combination, one with the other, and each indicated by a line word or syllable, said line words or syllables when united forming a complete cipher-word indicating the definitions contained in the desired message, as set forth.

6. A cipher - code comprising a series of groups or columns of definitions each of which is indicated by a line word or syllable, the definitions of any one group or column being capable of use with any one of the remaining groups or columns, arbitrary cipher-words being formed by uniting said line-words, as set forth.

7. A cipher-code comprising several series of definitions arranged in vertical columns, and individual line-words for each of said definitions also arranged in columns, the combination of any two of said line-words forming a complete cipher-word indicating the definitions contained in the desired message, as set forth.

8. A cipher-code consisting of a series of primary words or phrases arranged in columns and each indicated by a line-word, and a series of auxiliary words or phrases also arranged in columns and each indicated by a line-word, and two of said primary and auxiliary words or phrases being capable of grammatical combination, said line-words when united forming a cipher-word indicating the primary and auxiliary expressions intended to be so combined, as set forth.

In testimony whereof I have signed this specification in the presence of two subscribing witnesses.

ELMER F. CASSEL.
